UNITED STATES PATENT OFFICE.

LEOPOLD STICKLEY AND GRANT I. TAYLOR, OF SYRACUSE, NEW YORK, ASSIGNEES
TO STICKLEY MANUFACTURING COMPANY, OF EASTWOOD, NEW YORK, A CORPO-
RATION OF NEW YORK.

CONVERTIBLE BED.

Application filed January 20, 1925. Serial No. 3,569.

This invention relates to certain improvements in convertible beds.

The main object of the invention is the production of a bed structure that ordinarily 5 takes the form of a couch or single-bed, but is readily convertible into a double bed when desired, both sections of the bed in the converted form resting independent of the other solidly upon the floor, but equipped with co- 10 operating parts causing the elevation of one of said sections when the structure is re-converted into single bed form so that it no longer rests upon the floor, but is carried and supported by the other section.

15 Other objects and advantages relate to the details of the structure, all as will more fully appear from the following description, taken in connection with the accompanying drawings, in which:—

20 Figure 1 is a perspective view of a convertible bed of our invention.

Figure 2 is a section on line 2—2, Figure 1.

Figure 3 is a perspective view partially in section at one corner of the bed illustrating 25 the means for normally preventing separation of the bed sections.

Figure 4 is a section on line 4—4, Figure 1.

Figure 5 is a section similar to Figure 4 with the structure in double bed form.

30 The convertible bed of this invention primarily consists of a main frame —1— of rectangular form and consisting of preferably a rectangular angle iron framework of proper size to constitute a single bed and supported at its four corners by the corner-posts 35 —2—, —3—, —4— and —5—. The corner-posts —2— and —3— are preferably connected by a head-rail —6—, while the corner posts —4— and —5— are connected by foot-rail

40 —7—, and the corner posts —3— and —4— are connected by a back-rail —8—. All of these rails may be of any desired form, and of any ornamentation, and may, if desired, as shown, constitute the two sides and back of 45 a couch. The front posts —2— and —5— are connected solely through the medium of the front section of the angle iron framework.

50 This angle iron framework may be secured to the posts and to the head, foot and back rails in any suitable and desired manner, and as illustrated, carries a spring structure —9— suitable for constituting a spring bed in conjunction with the mattress —10—, which as

perhaps best illustrated in Figure 4, consists 55 of two similar connected sections, one adapted to be folded upon the other when the structure is used as a single bed.

The structure so far described constitutes 60 an ordinary single bed except for the provision of the couch-like rails —6—, —7— and —8— before described.

In addition to the single bed structure described, this convertible bed includes a second rigid rectangular framework —11— of 65 substantially the same size and form as the main rigid rectangular framework —1—. This second rigid framework for the purpose of this application is termed an auxiliary rigid rectangular framework, and as here illustrated, is of slightly greater width than the main framework —1— and its rear portion is adapted to move beneath the rear rail —8— as best illustrated in Figure 4, and this 70 enlargement in width is desirable in order that the framework —11— may be adapted to receive within it a third rigid rectangular framework —12— here termed a supplemental rigid rectangular frame.

75 And this supplemental frame is of substantially the same size and form as the main frame —1—, altho perhaps of slightly less width and slightly less length, to permit its reception within the framework —11— and the positioning of the latter framework below 80 and in substantial registration with the main framework —1—. The supplemental framework —12— carries a series of springs —13— constituting a spring-bed and adapted to be used in conjunction with one section of the 85 mattress —10— when the latter is unfolded as best illustrated in Figure 5.

90 Normally when the structure is utilized as a couch or single bed the supplemental framework —12— is collapsible within the framework —11—, as illustrated in Figure 4. When, however, the structure is utilized as a double bed, as illustrated in Fig. 5, the supplemental framework —12— is elevated to the level of the main framework —1— by 95 means of head and foot lever mechanisms —14—. These mechanisms are of identical construction, and each comprises a pair of oppositely disposed levers —15— carried by the rock-bar —16— mounted in the oppositely 100 disposed longitudinal angle-iron of the frame —11—. These two levers —15— are connected by cross-bars —17— and —18—, upon

the upper one of which the frame —12— normally rests. The front one of the levers —15— is formed with an extension —19— constituting a handle by means of which the lever structures can be rocked so that they lie in the framework —11— as illustrated in Figure 2 when the frame —12— is collapsed with in the frame —11— or can be moved to a substantially vertical position to thereby elevate the framework —12— to the level of the framework —1— as illustrated in Figure 5.

This particular elevating means constitutes no portion of the present invention.

The special novel features of the present construction will now be described. At each of the rear corners of the main frame —1— at the corner posts —3— and —4—, there is provided a comparatively short inclined track section —20—. These track sections may be formed of angle irons with their vertical sides secured to the respective posts —3— and —4— and the respective head and foot rails —6— and —7— as illustrated here by three screws or bolts —21— and the other angle of the angle iron —20— inclines upwardly from the horizontal as it extends rearwardly, for a purpose hereinafter described.

Each front corner of the main frame at the posts —2— and —5— respectively is provided with a second comparatively short track section —22— which may also be formed of angle iron having its vertical wall connected to the posts —2— and —5— respectively and the head and foot rails —6— and —7— respectively in any suitable manner, as by screws —23—. These track sections —22— are further provided with downwardly bent or formed portions —24— lying below the horizontal size of the angle irons constituting the track sections —22—. And as suggested, these track sections —22— have their side wall which constitutes their track portion substantially horizontal.

The auxiliary frame —11— is adapted during practically all of its movement to and from a position beneath the main frame —1— to move on and be supported by its own legs —44— provided with castors —25— and preferably these legs are supported at four respective points adjacent the four corners of the frame —11— by means of brace-bars —26— which extend from one angle iron to the other at the four corners of the bed, and as illustrated form triangles with the adjacent portions of the angle irons so that the supporting castors are within the frame —11—.

The angle irons at the head and foot of the frame —11— are formed as best illustrated in Figures 4 and 5 with downwardly pressed or counter-sunk portions —27— which lie slightly below the remaining portions of the angle irons, and below the lower plane of the framework —11—, and each of these head and foot angle-irons at the rear of or adjacent the rear of its depressed portion

—27— is formed with a dog —28— which may be formed by slitting the angle-iron and bending the produced free end downwardly, as indicated.

The operation of this structure so far described will be readily understood from the following:

When the frame —12— is collapsed within the frame —11— and the frame —11— resting upon its castors —25— is pushed rearwardly under the main frame —1—, it will, until it approaches the limit of its rearward movement, move upon its own castors upon the floor which independently supports both it and the main framework. When the rear rail of the framework —12— approaches the limit of its rearward movement, it will move over the lower forward end —29— of the track section —20— and further rearward movement will cause a slight elevation of the rear side of the framework —11— sufficient to lift the castor —25— from contact with the supporting floor.

At the same time the depressed portion —27— of the head and foot angle iron sections of the framework —11— will be brought into contact with the horizontal portion of the tracks —22— and the forward portion of the framework —11— will be elevated a distance sufficient to raise the front castors —25— from contact with the supporting floor and at this point the supplemental framework is supported entirely on and beneath the single bed structure, including the main framework. When the limit of rearward movement has been reached where the front board —30— contacts with the main framework —1—, the dog —28— will drop against and at the rear of the horizontal portion of track section —22— and will under normal circumstances prevent separation of the supplemental framework from the single bed structure. When it is desired to effect such separation, it is only necessary to lift the forward portion of the framework —11—, as by means of the front board —30— so as to free the dog —28— from engagement with the rear end of track section —22— when the framework —11— may be freely withdrawn, and after movement of a few inches will rest and roll upon its supporting castors —25—.

The front board —30— as shown, is carried by the front longitudinal angle-iron of frame —11— and is preferably of a width so as to extend above the main frame —1— and slightly overlap the mattress —10— so as to produce a finished structure in single-bed form.

It is found desirable to normally limit the outward movement of the framework —11— in the course of producing a double bed in order to prevent separation of the sections, and for this purpose the rear longitudinal angle iron of the framework —11— is formed with a latch —31— having one end pivotally

connected to the angle iron as by rivet or bolt —32— and its other end lying below the head or foot section respectively of the framework —11— so as to come into contact with the flange —24— on the track —22— when the frame —11— has been drawn out from beneath the frame —1— to the desired position for forming a double bed.

As suggested, the rear longitudinal rail 10 of the framework —11— at both the head and foot of the bed is formed with a latch —31—. One of these latches may be rigidly secured to the angle iron as by rivet —32— or series of rivets. One of them however, should be secured 15 to the angle iron in a movable manner so as to permit it to be moved to a position where it will not engage the flange —24— should it be desirable to separate the frame —11— from the frame —1— and for this 20 purpose as best shown in Figure 3, in addition to the pivotal bolt —32— a second removable connection is shown to normally prevent pivotal movement in the form of a removable bolt —33— normally held in place 25 by a cotter-pin, as illustrated.

It will be obvious from the above that there is here illustrated a structure capable of use as either a single or a double bed, both sections of which during motion of their relative movement are supported independently 30 of each other upon the floor, but during a small portion of their movement and while

the two sections are in registration one beneath the other, the one is supported on and by the other independently of the floor so as 35 to produce a single bed structure of a unitary character, and adapted for joint movement by the mere movement of the single bed structure including the main frame, and altho we have shown and described a specific 40 structure as illustrative of an embodiment of our invention, we do not desire to restrict ourselves to the details of the structure or the parts thereof, as various changes may be made within the scope of the appended 45 claim.

We claim:

The combination with a single bed structure having a spring-supporting frame, of a collapsible single bed structure capable in 50 collapsed condition of being moved underneath said spring-supporting frame, and inclined guides at the rear side of the single bed structure for elevating the rearside of the collapsed bed structure from contact with the 55 floor, additional guides at the front of the single bed structure, and means on the collapsible bed structure for causing elevation of the front of the collapsible bed structure when moved over said last-named guides. 60

In witness whereof we have hereunto set our hands this 29th day of December, 1924.

LEOPOLD STICKLEY.
GRANT I. TAYLOR.
